Design No. 4,952, dated May 30, 1871.

DESIGN FOR A CARPET-PATTERN.

The Schedule referred to in these Letters Patent and making part of the same.

I, WILLIAM KERR, of Philadelphia, county of Philadelphia, State of Pennsylvania, have invented or produced a Design for a Carpet-Pattern, of which the following is a specification.

The figure in the accompanying drawings represents sufficient of a carpet-pattern to illustrate my design, which consists mainly of tablets A, united at the corners by short inclined bands B, which inclose between the said tablets spaces C, containing the checkered ground-work *a* and central foliated figures *b*, as plainly shown in the drawings.

Each of the tablets A has a border, *c*, of the character represented, and a central scroll-like ornament, *d*.

Irrespective of the colors employed,
I claim—

The design for a carpet-pattern, substantially described and as represented in and by the accompanying drawings.

In testimonay whereof I have signed my name to this specification in the presence of two subscribers.
